Filed June 3, 1960, Ser. No. 33,769

8 Claims. (Cl. 313—92)

This invention relates to color image-producing cathode ray tubes of the index type wherein the color image is produced by successive and repetitive electron beam scanning of elements emissive of light of different primary colors, such as red, green and blue, and wherein an index signal is also produced which is utilized to effect coordination between instantaneous beam modulation and beam position, such coordination being essential for proper color rendition. Such cathode ray tubes are now well known. They are useful, for example, in color television receivers. This invention relates to beam-intercepting structures or screens for such cathode ray tubes.

The beam-intercepting structure of a tube of this type preferably comprises phosphor stripes in successive triplets which extend transversely to the direction of line scanning motion of the electron beam, the stripes of each triplet being successively emissive of light of different colors as the beam traverses them. The "color writing" frequency is the nominal rate at which the writing beam traverses the color triplets, i.e. the number of triplets traversed per second. By way of example, this frequency may be 6 mc.

The index signal is produced by electron beam impingement of index elements which may also be in the form of stripes extending transversely to the direction of line scanning. They may be composed of a fluorescent material, such as zinc oxide, having a spectral output in the non-visible light region, and the index signal may be derived from a suitable photoelectric cell arranged, for example, in a side wall portion of the cathode ray tube out of the path of the electron beam and facing the beam-intercepting structure. Alternatively, the index signal may be produced by secondary electron emission as well understood in the art.

In operation of certain color image-producing cathode ray tubes of the type here involved, the index elements tend to cause production of an undesirable visible pattern in the color image. For example, with a certain desirable form of the beam-intercepting structure as hereinafter described, the index elements necessarily overlap or "shadow" certain of the color elements and tend to cause production of an undesirable visible pattern.

The principal object of the present invention is to provide an improved beam-intercepting structure, the beam scanning of which does not produce a visible pattern in the color image.

Another object of the invention is to provide a highly efficient beam-intercepting structure.

Other objects and features of the invention will be apparent from the description to follow.

In one form of beam-intercepting structure according to this invention, the structure is caused to be non-productive of the undesirable visible pattern in the color image by a combination of dimensioning of the shadowed elements and adding other shadowing elements. In another form of beam-intercepting structure according to this invention, the structure is caused to be non-productive of the undesirable visible pattern simply by dimensioning of the shadowed elements.

The invention may be fully understood from the following detailed description with reference to the accompanying drawing wherein:

2

FIG. 1 is a greatly enlarged fragmentary sectional plan view of a beam-intercepting structure of a desirable form in which, however, the index elements cause production of the aforementioned undesirable visible pattern in the color image;

FIG. 2 is a similar view of a beam-intercepting structure of the same general form but embodying one form of this invention; and

FIG. 3 is a similar view of a beam-intercepting structure embodying another form of this invention.

Referring first to FIG. 1, the beam-intercepting structure there shown comprises a transparent substrate 10 on which the color phosphor stripes are deposited. The substrate 10 may be the faceplate of the cathode ray tube or it may be a transparent member in proximity to the faceplate. Red light-emissive phosphor stripes are shown at 11; green light-emissive phosphor stripes are shown at 12; and blue light-emissive phosphor stripes are shown at 13. Since the red light-emissive phosphor is less efficient than the green light-emissive and blue light-emissive phosphors, the stripes 11 are made wider than the stripes 12 and 13 in order to achieve white balance. On the rear of the color phosphor stripes there is provided a conventional electron-permeable and light-reflecting layer 14. This layer, which may be composed of aluminum for example, increases the brightness of the image by reflecting toward the observer those rays of light emitted from the rear of the color phosphor stripes in response to impingement of the electron beam thereon. The index stripes 15 are deposited on the layer 14, and the latter also serves to separate the index stripes from the image-producing stripes.

In a beam-intercepting structure of this character, it is desired to have the index stripes 15 disposed behind alternate spaces between the color phosphor stripes. This is intended to serve two purposes—namely, (a) to produce an index signal having a frequency $3/2f$ where f is the color writing frequency as explained above, and (b) to avoid "shadowing" of the color phosphor stripes by the index stripes. With respect to the production of a $3/2f$, i.e. 9 mc., index signal, this is a so-called "ambiguous" signal which is converted to a signal having the frequency f . There is no need to explain here the reason for the production of the $3/2f$ signal. For an explanation of this, reference may be had to the co-pending application of F. P. Keiper et al., Serial No. 797,684, filed March 6, 1959, assigned to the assignee of the present application. With respect to "shadowing" of the color phosphor stripes, if any of the index stripes are disposed behind or overlap any of the color phosphor stripes, they (the index stripes) decrease the electron impingement on the overlapped or "shadowed" color phosphor stripes and hence decrease the light-emission of the stripes. While this is undesirable, it necessarily results from the widening of the red light-emissive stripes 11, as may be seen in FIG. 1, which will now be explained.

The distance between the center lines of two consecutive red light-emissive stripes represents one cycle of color writing, or 360 color degrees. Thus the distance d_1 represents one cycle and the distance d_2 represents the next cycle. Since this spacing of the red light-emissive stripes must be maintained to maintain the proper color writing frequency, increasing the width of the red light-emissive stripes necessarily decreases the width of the spaces between each of those stripes and the adjacent blue and green light-emissive stripes, resulting in overlapping or "shadowing" of the red light-emissive stripes by some of the index stripes. This reduces the light output of the red light-emissive stripes and causes production of an undesirable visible pattern in the color image as will now be explained.

First it should be noted that at the color writing frequency, 6 mc., the resolution ability of the human eye is inadequate for discernment of a pattern in the color image, but at substantially lower frequencies a pattern becomes visible to the human eye. In the screen structure of FIG. 1, the cycle d_1 is representative of alternate color cycles and the cycle d_2 is representative of the other alternate color cycles. That is to say, the color cycle following d_2 is the same as d_1 , the next color cycle is the same as d_2 , and so on. As the beam traverses the d_1 color cycles it does not encounter any shadowed areas, but as it traverses the d_2 color cycles it encounters shadowed areas of the red light-emissive stripes. Thus in alternate color cycles the emitted red light output of the screen is lower than it is in the other alternate color cycles, and this produces a pattern at one-half the color writing frequency, i.e. 3 mc., which is within the resolution capability of the human eye and which appears as a coarse line structure in the color image.

Referring now to FIG. 2, there is shown a beam-intercepting structure or screen according to one embodiment of the present invention. This structure is generally of the form of that of FIG. 1 but it embodies features according to this invention. The elements corresponding to those of FIG. 1 are designated by the same reference numerals with the addition of the suffix "a".

In the structure of FIG. 2, the red light-emissive stripes 11a are widened further on both sides to abut the adjacent blue and green light-emissive stripes, and additional stripes 16 are provided as shown. These stripes may have substantially the same electron transparency as the index stripes 15a but they should not interfere with the production of the index signal. For example, where the index stripes are emissive of invisible light, stripes 16 should be composed of a material, such as an unactivated phosphor, which will not emit light.

It will be seen that with this arrangement there are two shadowed portions of each red light-emissive stripe, and as the electron beam sweeps across the stripes 15a and 16, an invisible pattern at twice the index frequency, i.e., 18 mc., is produced which, of course, is not objectionable because it is not seen. Moreover, even though the red light-emissive stripes are further shadowed, their light emission is actually greater than in the case of FIG. 1 due to their increased width. It should be noted particularly that in this structure the light output of the red light-emissive stripes is equalized in the successive color cycles. Therefore this screen structure does not produce the undesirable visible pattern which is characteristic of the structure of FIG. 1.

Referring now to FIG. 3, there is shown a beam-intercepting structure according to another embodiment of this invention. This structure is also generally similar to that of FIG. 1 and the elements are designated by the same reference numerals with the suffix "b" added. In this instance, the red light-emissive stripes 11b are widened in the areas adjacent the index stripes. While the added portion of each red phosphor stripe is shadowed, the light output is increased. For example, suppose that the index stripes are 50 percent transmissive of electrons. In FIG. 1 each index stripe covers 30 color degrees of the red phosphor, which is as if 15 color degrees had been removed. In FIG. 3 this is counteracted by adding 30 color degrees of red phosphor adjacent each index stripe.

Thus in FIG. 3 the light output of the red light-emissive stripes is uniform in the successive color cycles. That is to say, it is the same in the d_2 color cycles as it is in the d_1 color cycles. Therefore as the electron beam scans the screen there is no undesirable visible pattern as in the case of FIG. 1.

It will be seen from the foregoing description that this invention provides a screen which is non-productive of an undesirable visible pattern by equalizing the light output of the shadowed elements in successive color cycles.

It will also be seen that in both of the embodiments of FIG. 2 and 3 the index elements are each adjacent to and coextensive with a portion of a red light-emissive stripe; and FIG. 2 is further characterized by the added stripes 16.

While certain embodiments of the invention have been illustrated and described, it will be understood that the invention is not limited thereto but contemplates such modifications and further embodiments as may occur to those skilled in the art.

10 I claim:

1. A color image-producing screen having colored light-emissive elements which are scanned by an electron beam in successive color cycles at a predetermined color writing frequency and also having index elements at least some of which overlap portions of elements emissive of light of a particular color and tend to produce a visible pattern at a frequency lower than said writing frequency, said screen being characterized by structure for causing the light output of the latter elements to be substantially uniform or equal in the successive color cycles so that no undesirable visible pattern is produced in the color image by virtue of the shadowing effect of the overlapping index elements.

25 2. A color image-producing screen according to claim 1, wherein the index elements are adjacent to and coextensive with portions of said elements emissive of light of a particular color.

30 3. A color image-producing screen according to claim 2, wherein additional elements are provided on the screen at least some of which overlap portions of said elements emissive of light of a particular color, said additional elements having substantially the same electron transparency as said index elements and serving to prevent production of an undesirable visible pattern in the color image.

35 4. A color image-producing screen having colored light-emissive stripes which are scanned transversely by an electron beam in successive color cycles at a predetermined color writing frequency and also having index stripes which in alternate color cycles overlap portions of stripes emissive of light of a particular color and tend to produce a visible pattern at one-half the writing frequency, said screen being characterized by structure for causing the light output of the latter stripes to be substantially uniform or equal in the successive color cycles so that no undesirable visible pattern is produced in the color image by virtue of the shadowing effect of the overlapping index stripes in alternate color cycles.

50 5. A color image-producing screen according to claim 4, wherein said stripes emissive of light of a particular color are sufficiently wide to compensate for the shadowing effect of said overlapping index stripes.

55 6. A color image-producing screen according to claim 4, wherein the index stripes are adjacent to and coextensive with portions of said stripes emissive of light of a particular color.

60 7. A color image-producing screen according to claim 6, wherein additional stripes are provided on the screen at least some of which overlap portions of said stripes emissive of light of a particular color, said additional stripes having substantially the same electron transparency as said index stripes and serving to prevent production of an undesirable visible pattern in the color image.

65 8. An electron beam-intercepting structure for a color image-producing cathode ray tube, comprising a transparent substrate, stripes supported by said substrate which are successively and repetitively emissive of light of different colors in response to electron beam impingement, 70 the stripes emissive of light of one color being wider than the other stripes, light-emissive index stripes each adjacent to and coextensive with a portion of one of said wider stripes, and other stripes not emissive of light each adjacent to and coextensive with another portion of one of said wider stripes, said other stripes having sub-

stantially the same electron transparency as said index stripes.
